TOOL FOR REMOVING TUBULAR MEMBERS

Arthur G. Gifford, Rochester, N. Y., assignor of
one-half to Anthony A. Hasselwander, Roch-
ester, N. Y.

Application April 6, 1935, Serial No. 15,054

Renewed December 28, 1936

5 Claims. (Cl. 81—72)

This invention relates to tools for removing tubular members such as hydrant barrels, well casings etc. and is especially adapted for use in the removal of a broken barrel from a damaged hydrant to facilitate a quick and inexpensive repair of the hydrant.

It frequently happens that a hydrant barrel is severed at or below the street or sidewalk level, in which case the hydrant cannot be repaired without breaking the pavement or sidewalk and digging a hole, which must frequently be large enough to render the shoe or lower end of the hydrant barrel accessible and removable by means of a wrench attached to the outside thereof. The shoe of a hydrant is usually at a considerable distance below the pavement or sidewalk line, and accordingly it is a laborious and expensive operation to replace the broken barrel section. My invention has for its principal object the provision of a tool adapted to grip the broken barrel section on the inside a short distance from the end which is threaded into the shoe so as to permit the turning of the barrel below its fracture with the grip of the tool at a point where it can most efficiently secure the immediate removal thereof.

This and other objects and attendant advantages will become more readily apparent from the detailed description thereof which follows, reference being had to the accompanying drawings in which

Figure 1 is a vertical sectional view of a broken hydrant with my tool inserted thereto ready for the removal thereof.

Figure 2 is an enlarged horizontal sectional view of the tool, the section being taken on the line 2—2 of Figure 1.

Figure 3 is an enlarged horizontal sectional view of the tool taken on the line 3—3 of Figure 1.

Figure 4 is an enlarged vertical sectional view of the tool taken on the line 4—4 of Figure 1.

Figure 5 is an enlarged horizontal sectional view of the tool taken on the line 5—5 of Figure 1.

In the several figures of the drawing like reference numerals indicate like parts.

Referring to Figure 1, it will be seen that if the barrel 10 of the hydrant is severed below the pavement or sidewalk line 11, as at 12, the removal of the barrel becomes a matter of considerable difficulty. Heretofore it has been the customary practice to excavate around the fire hydrant to a depth sufficient to render accessible the upper end of the broken section of the bar-

rel and it is often necessary to dig down as far as the shoe 13.

This is entirely eliminated with the use of my tool which as illustrated in Figure 1 comprises the tubular shank 14, provided with the square head 15 at the upper end and a centrally hollow gripping head 16 at the lower end. A tubular locating and spacing extension 17 projects from the head 16 and forms a continuation of the hollow shank 14 in order to permit the valve stem 18 of the hydrant valve 19 to telescope into the tool and have the end of the extension 17 rest on the spider 20 of the valve sleeve 21. In this way the gripping head 16 is automatically spaced so as to be located above the enlarged lower end of the barrel 10 which is threaded into the shoe 13. This prevents the gripping head from entering the enlarged end of the barrel so that the expansion of the gripping jaws cannot lock the head into the barrel when it is inserted thereinto.

The gripping head is provided with an annular channel 22 in which the gripping jaws 23, 23 are mounted. Each gripping jaw has the square shank of a bolt 24 projecting therethrough so as to turn therewith and the bolts are suitably journaled in the gripping head, and are provided with a square head 25 at the top and a cotter pin 26 at the bottom so as to lock the bolt and its jaw into the gripping head and provide for a swinging movement of the jaw in the annular channel thereof.

As illustrated in Figure 2 each of the jaws is provided with a pair of eccentric gripping faces 28 and 29 which curve toward each other and meet at the outer end of the jaws. Each jaw is thus pointed and the serrations or teeth of the gripping faces are cut so as to have them point toward the outer end of the jaw. In this way the jaws may be turned to engage the inside of the tube or barrel with either one or the other of the gripping faces and turn the tube in whichever direction the jaws are pointed in the gripping head on the rotation thereof in that direction.

The jaws are yieldingly held against the surface to be engaged thereby by a pair of springs 30, 30 which are attached to one corner of each of the square heads of the bolt 24 and extend from this corner in opposite directions, one to an anchoring post 31 on one side of the bolt and the other to an anchoring post 32 on the other side of the bolt. Each jaw is thus normally held in a neutral position in which its pointed end projects radially from the gripping

head. To insert the head into the barrel it is turned at the broken end in the direction opposite to the movement which is necessary for the removal of the barrel and this movement swings the jaws to one side against the tension of one of the springs until the jaws are turned to one side and can enter the barrel. The gripping head is then moved down into the barrel until the end of the extension 11 rests on the spider 10 of the valve sleeve as above described and locates the gripping head just above the enlarged portion of the barrel. The wrench 33 is then placed over the square head 15 and the tubular shank turned in the direction in which the barrel 15 unscrews itself from the shoe 13. This action slightly turns the jaws and wedges it against the inside wall of the barrel so that the teeth thereof dig into the wall of the barrel and finally turn the barrel. If for any reason it is necessary to rotate the barrel or tube in the opposite direction after it has been partially unscrewed the tool is removed therefrom and then reinserted with the jaws pointed in the opposite direction so that the jaws are wedged and grip the wall when the tool is rotated in the direction in which the barrel is threaded back into the shoe.

For the purpose of holding the shank of the tool centrally in the broken barrel or tube a guide flange 34 is mounted to slide on the tubular shank and carries a pair of cross members 35 and 36 which are adapted to rest on the upper edge of the broken barrel and hold the flange in place therein. The guide flange 34 is 35 split and the two halves are held together by the bolts which hold the cross members 35 and 36 in place thereon. In this way the guide flange can be mounted to the shank between the large gripping head at one end and the square wrench head at the other end.

40 I claim:

1. A tool for removing a hydrant jacket having a valve mounted in the bottom of it and a valve stem extending upwardly therefrom centrally of the jacket, said tool comprising a tubular shank adapted to telescope over said valve stem, a hollow gripping head at the end of said tubular shank and a pilot sleeve forming an extension of said hollow shank depending from said gripping head to be supported by said valve so as to have said tubular shank, said head and pilot sleeve surround substantially the full length of said valve stem and support said gripping head a predetermined distance above said valve within said jacket, a guide member on said hollow shank above said gripping head to en-

gage said jacket at the free end thereof and cause said shank to be held centrally in the jacket above and below said gripping head.

2. A tool for removing long tubular members held threaded in place at one end thereof and having a valve stem centrally thereof, said tool comprising a tubular shank, a gripping head formed on said shank, a plurality of gripping jaws uniformly and circularly spaced concentric with the shank and mounted to eccentrically swing on said gripping head to project therefrom, a locating member depending from said gripping head to centrally support said head from a point below the gripping head at a predetermined distance from the threaded end of the tubular member, and a guide member slidably mounted on said shank above said head so as to engage into the tubular member and hold said shank centrally in the tubular member above the gripping head and means carried by 20 said guide member to hold it in position on the tubular member.

3. A tool for removing tubular members as set forth in claim 2 in which said gripping jaws have oppositely curved gripping faces and means 25 for causing the jaws to normally project radially outward from the shank so as to engage the inner wall of the tubular member and have the jaws swing in one direction on entering the tubular member by rotating the shank in the 30 opposite direction and then cause the jaws to grip the inner wall of the tubular member when the direction of rotation of the shank is reversed.

4. A tool for removing tubular members as set forth in claim 2 with spring means for normally holding said gripping jaws in a radially projected position.

5. A tool as set forth in claim 2 with each of said jaws mounted on a bolt, a substantially 40 square shank provided on said bolt and projecting thru the jaw to hold said jaw keyed thereto, journal means supporting each bolt above and below its jaw, a head formed on each bolt and spring means connected to said head and extending to opposite sides thereof to hold said jaw in a yieldingly predetermined radially projected position, said jaws collectively turning in either direction on engagement thereof with the inner wall of the tubular member to cause 50 the jaws to swing in one direction on entering the hollow member by rotating the shank in the opposite direction and have the jaws grip the inner wall of the tubular member when the direction of rotation of the shank is reversed. 55

ARTHUR G. GIFFORD.
